FLOATING DOCK

Henry O. Foss, Tacoma, Wash.

Application April 14, 1943, Serial No. 483,022

7 Claims. (Cl. 61—48)

This invention relates to floating docks and similar structures.

As is well known, it has been the common practice to build many types of docks by employing conventional piling driven into position. Such piling has been employed for supporting wharves and for forming ferry boat slips substantially fitting one end of the ferry boat to guide it into position. Ordinary piling is open to several objections in actual practice, and this is particularly true of the use of piling for forming ferry boat slips. In the first place, the piling has no support between the bottom of the water and the point at which forces are transmitted at right angles thereto by boats moving into landing position. This is particularly disadvantageous where ferry boat slips are built in relatively deep water, as is often necessary.

Inasmuch as forces are exerted against the piling at points remote from the points of support thereof, the piling are subject to being broken off at the ground. Piling employed in salt water is subject to attack by marine borers, such as teredos, and accordingly the piling has very limited life. In actual practice piling used in salt water will not last over six months because of the weakening and breaking of the piling due to the action of marine borers.

Where piling becomes broken at the ground line, it is impossible to replace it with piling driven in the same position due to the impossibility of removing the lower end of the pile from the ground. Thus substantial difficulties as well as great expense are involved in maintaining piling, and particularly those used as ferry boat slips.

It is wholly impracticable to employ floating docks such as ferry boat slips by securing them by means of anchors. As is well known, it is impossible to moor a boat to an anchor by means of a short chain or cable since the forces transmitted to the anchor are largely vertical and will dislodge the anchor. It is therefore well known that the mooring of boats and buoys requires relatively long lines in order that the forces transmitted to the anchor may be largely horizontal whereby the anchor will hold against dislodgment. The use of such long lines renders it wholly impracticable to fix floating docks in position by such means.

An important object of the present invention is to provide a novel floating dock construction which eliminates the disadvantages of the use of piling and serves to hold the dock relatively

stationary without the use of conventional anchors.

A further object is to provide a novel dock construction wherein a floating dock is employed and is held in position by means of chains or the like connected to piling sunk wholly beneath the surface of the ground where it is protected from borers and is not subjected to unsupported strains exerted against the piling transversely thereof.

A further object is to provide such a floating dock which is effectively held in position against any reasonable strains which might be exerted thereagainst while at the same time cushioning the landing of a boat, thus minimizing damage to the boat and dock.

A further object is to provide a floating dock having novel means for holding it in position whereby it remains relatively accurately in position regardless of wind, tides, etc.

In the drawings I have shown two general embodiments of the invention. In this showing

Figure 1 is a plan view of a dock lay-out,

Figure 2 is a front elevation of the same,

Figure 3 is a vertical sectional view showing a pile, in elevation, arranged ready to be sunk in the earth,

Figure 4 is a similar view showing a pile driven in position,

Figure 5 is a similar view showing the driven pile with the upper end removed therefrom and with the chain connected to a portion of a floating dock,

Figure 6 is a plan view of a modified type of dock lay-out, and

Figure 7 is a perspective view of one of the buoys employed in Figure 6.

Referring to Figure 1, the numeral 10 designates the ground adjacent a body of water 11, the shore line being indicated by the numeral 12. A floating dock 13, to be referred to later, is arranged preferably relatively close to the shore line. A conventional approach to the dock is indicated by the numeral 14 and an apron 15 has one end connected to the approach and its opposite end bearing on the top of the dock 13. The apron 15 is of such nature as to permit its dock end to move upwardly and downwardly as the tide ebbs and flows.

In the present instance the dock 13 has been shown as being of a truncated V-shape to serve as a slip to receive an end of a ferry boat, shown in outline in Figure 1 and indicated by the numeral 16. It will become apparent that the in-

vention is not limited to a ferry boat slip but may be employed in connection with floating buoys and docks of any desired type. The dock is shown as being moored by means of a plurality of flexible elements, preferably heavy chains, for a reason to be described. At its remote sides the dock is provided with mooring chains 17 and the approach ends of the dock are shown as being provided with mooring chains 18 which diverge from each other toward the dock. At its land end, the rock is shown as having its opposite corners connected to mooring chains 19 which may sharply diverge toward the shore line. The dock may also be provided with inside mooring chains 20 extending toward each other away from the shore line.

The number and arrangement of mooring chains will depend upon the type of dock, conditions at the place of installation such as tides, etc., and the size of the dock and the size of the boats intended to land at the dock.

The various mooring chains have their lower ends secured to a novel type of piling shown in finished form in Figure 2. The method of installing the piling is shown in Figures 3, 4 and 25 5, and reference is made to these figures. A pile indicated as a whole by the numeral 21 is grooved intermediate its ends as at 22 to provide a lower anchoring end 23 and an upper end 23' to be later removed in a manner to be described. Near 30 the extremity of the pile end 23 one end of a flexible element, preferably a heavy chain, 24 is turned around the piling, preferably twice, and half hitches are taken in the chain to insure a permanent connection of the chain to the pile. The end of the chain is secured to the pile by a bolt 25 extending through the pile, and the half hitches and the turns of the chain about the pile tend to cause a binding of the chain about the piling without transmitting undue strains to the bolt 25.

The pile is placed in position as shown in Figure 3 in a vertical position with the lower extremity of the end 23 resting on the bottom or surface of the earth 26. The pile will be placed and held in such position with respect to a pile driver by which the driving of the pile is ready to be effected in the customary manner. The free end of the chain 24 will be supported at some point on the pile driver in any suitable manner. The pile is then driven into the bottom 26 until the groove 22 is at a level slightly below the surface of the bottom 26, as shown in Figure 4. The cutting of the groove 22 will not interfere with the transmission of vertical thrusts through the pile to sink the lower end thereof into the earth. However, the groove weakens the pile and permits the exertion of a transverse strain to the upper end of the pile to break it off in the plane of the groove 22. This operation is performed and the upper end 23' of the pile is then removed.

While the removal of the upper end of the pile provides access of the water to the upper extremity of the lower pile end 23, it will be obvious that the earth will soon shift and will completely cover the pile as shown in Figure 5. The pile end 23 thus becomes a permanent pile completely embedded in the earth and protected against the action of marine borers.

With the float in position and a sufficient number of properly placed permanent piles driven into the earth, the chains of the respective piles may be connected by any suitable means to the proper points on the float. Each chain 24 be-

comes one of the mooring chains referred to in connection with Figure 1, or any other mooring chains depending upon the type of installation. The float may be provided with any type of eyes 5 27 for connecting the mooring chains thereto at the proper points.

The invention has been particularly described in connection with one type of dock, namely, a floating unitary ferry boat slip. The invention is obviously applicable to other types of docks and in Figures 6 and 7 the invention has been illustrated in connection with a ferry boat slip made up of a plurality of floats or buoys. Referring to Figure 6, the numeral 28 designates an approach having an apron 29 connected at one end thereto. In this type of installation, wherein a number of relatively small floats are employed, it is impracticable to employ an apron having a vertically movable end as in Figure 1. Accordingly the dock end of the apron 29 may be supported in any suitable manner, as by means of posts 30 driven into the ground.

The ferry boat slip shown in Figure 6 may be made up of a plurality of floats 31 arranged parallel to each other. Each float is provided with at least four mooring chains 32, and these chains may be angularly arranged relative to each other and relative to the float. For example, the chains may be arranged radially with respect to the center of each individual float, or they may diverge from each other at other angles, depending upon individual conditions of installation. At least the outermost float 31 is preferably provided with an additional mooring chain indicated by the numeral 32' and this chain may be arranged parallel to the adjacent chain which extends inwardly from the inner corner of the float at the side thereof remote from the shore. This arrangement provides greater stability for the floats which take the maximum thrusts when a boat is landing, as will be apparent.

Each float 31 is preferably provided with a fender in the form of a vertical stanchion 33 extending over the end of the float adjacent the inside of the dock. These fenders are adapted to be engaged by the ferry boat guard, and each stanchion may be braced as at 34.

The operation of the form of the invention shown in Figures 1 and 2 is as follows:

A ferry boat approaching the slip will be steered with reasonable accuracy directly into the slip. It is well known that a conventional ferry boat slip functions to guide the boat into position as it approaches its landing position in the slip, and the present device functions in the same manner except that it cushions the force exerted against one side or the other of the slip if the boat does not move accurately thereinto. The arrangement of the anchor chains and their piling is such as to prevent substantial movement of the slip and they are disposed to the best advantage to oppose the greatest forces exerted thereagainst. The anchoring means including the chains 17 at one side of the float oppose movement of the float in the opposite direction. For example, assuming that the boat in entering the slip first contacts with the left side thereof as viewed in Figure 1, the right hand chains 17 and their piling will oppose displacement of the 60 float toward the left. The same movement will be opposed by the chains 18 and 20 and their associated piling. All of the chains shown in Figure 1 except the chains 19 extend from their 65 points of connection with the float away from the shore line and angularly with respect to the 70 75

axes of the boat and the slip 13. Therefore half of these chains will always oppose lateral displacement of the float when the boat enters the slip, and all of them oppose movement of the float toward the shore when the end of the boat engages the inner end of the float. The chains 19 are not subjected to any substantial force, and two of these chains and their associated piling usually will be all that is necessary to prevent movement of the float away from the shore.

The cushioning action provided by a floating dock over a relatively rigid dock is obviously advantageous. This is particularly true in ferry boat slips since ferry boats are not landed as carefully as other boats as large or larger. Where stationary piling is employed, a pile will be frequently broken by the exertion of force thereagainst above the water, there being no support for the pile between the point of contact of the boat and the earth beneath the water. Such an arrangement does not provide the cushioning action which is present in the structure described, and the latter accordingly minimizes damage both to the float and to the boat.

I have found that difference in water levels due to changes in tide conditions and consequent differences in the degrees of slackness of the chains do not substantially affect the operation of the construction. In Figure 2 the float and several of the chains have been shown in solid lines as being taut, which is the condition approximately present at flood tide. It will be clear, of course, that if the chains are ever taut, it will be at flood tide, although tautness even at flood tide is not necessary or even desirable. The float and the chains have been shown in dotted lines in the approximate positions that would occupy at ebb tide. Under such conditions there will be substantial slack present in the chains. However, the use of heavy chains provides heavy weights acting downwardly to tend to maintain the minimum horizontal distance between the ends of each chain, the weights of the chains thus opposing any displacement of the dock. In other words, the weights of the chains acting vertically causes resultant forces at the ends of the chains to tend to pull the piles and the dock toward each other. These resultant forces are balanced on opposite sides due to the uniform angles of divergence from the vertical of the oppositely arranged and oppositely acting chains. The downwardly acting weights of the chains thus tends to center the dock in its proper position while at the same time providing for limited movement of the dock under the impact of a boat landing in the dock off center. The opposing of the horizontal displacement of the dock is, in effect, a cushioning action, as stated, thus preventing damage either to the boat or the dock. To be properly effective in providing the centering and cushioning action, the chains should be always sufficiently slack, whereby the downwardly acting weights of the chains will transmit the proper resultant forces to the piles and to the float. Therefore, at least a reasonable degree of slack in the chains is the normal condition, the chains preferably never being perfectly taut unless the dock is displaced to the limit of the slackness of one or more of the chains. Where there are extreme differences in water levels between ebb and flood tides, longer chains may be employed, if necessary, with the respective piling arranged further from the float, in which case a given downward movement of

the dock will result in a minimum slackening of the chains at ebb tide.

In the form of the invention shown in Figures 6 and 7 a number of individual floats are employed instead of the unitary float structure in Figures 1 and 2. These floats are individually connected to the piling and are adapted to partake of limited movement relative to each other. The chains of the floats are preferably disposed as previously described to afford the maximum holding effect to minimize displacement of the floats upon the exertion of forces thereagainst as the boat enters the slip. Where individual relatively small floats are employed they are disposed in any desired manner relative to each other in accordance with the use to which the dock is to be put. For example, the floats may be arranged as in Figure 6 to define a ferry boat slip, and each is preferably provided at its inner end with one of the fender stanchions to minimize damage to the relatively light floats, or to provide means projecting above the float a sufficient distance to be engaged by the guard rail of the boat.

25 It will be apparent that the invention may be designed for use with any type of boat landing. For example, a long straight float may extend transversely of the shore line to act as an ordinary wharf; spaced parallel floats may be employed on opposite sides of such wharf to define slips to receive pleasure or fishing boats, etc.

In actual practice it has been found that the piling when completely buried in the ground requires a force of approximately eighty tons to dislodge one of the piles when the dislodging force acts vertically. Obviously, the force required to dislodge a pile progressively increases as the force is applied at progressively increasing angles to the vertical. By using angularly arranged flexible members or chains, therefore, forces are applied to the piling under such conditions as to make it practically impossible to dislodge the piling. At the same time this arrangement functions to maintain a float or dock relatively accurately in position regardless of variations in water levels, particularly where heavy chains are employed. The present invention compares favorably in its cost of installation to installations of conventional piling, especially with respect to ferry boat slips, since fewer piles are employed. Moreover, the installation once having been made may be considered to be permanent, as distinguished from conventional piling. The use of the invention is therefore far more satisfactory and costs materially less over long periods of time since there is no deterioration or destruction of the piles buried in the ground beneath the water.

60 It is to be understood that the forms of the invention herewith shown and described are to be taken as preferred examples of the same and that various changes in the shape, size and arrangement of parts may be resorted to without departing from the spirit of the invention or the scope of the subjoined claims.

65 I claim:

1. A dock construction comprising a floating dock unit, a plurality of anchoring elements completely embedded in the ground beneath the water, and normally slack flexible elements connecting said dock unit to said anchoring elements at points spaced from the top surface of such ground, said flexible elements being connected to the dock unit at oppositely facing points and diverging downwardly at substantially uniform angles to the vertical.

3.2. A dock construction comprising a floating dock unit, a plurality of anchoring elements completely embedded in the ground beneath the water, and normally slack relatively heavy chains connecting said dock unit to said anchoring elements at points spaced from the top surface of such ground, said relatively heavy chains being connected to the dock unit at oppositely facing points and diverging downwardly at substantially uniform angles to the vertical.

3.3. A dock construction comprising a floating dock unit, vertical anchoring elements driven into the earth beneath the water and having their upper ends terminating beneath the surface of the earth, and normally slack relatively heavy chains connected at their upper ends to said dock unit at oppositely facing points thereon, said chains diverging downwardly at substantially uniform angles to the vertical and being connected at their lower ends to said anchoring elements beneath said surface of the earth.

3.4. A dock construction comprising a plurality of floats cooperating to form a dock of predetermined shape, a plurality of anchoring elements completely embedded in the earth beneath the water, and at least two normally slack flexible elements connected to each float at oppositely facing portions thereof and diverging downwardly at substantially uniform angles to the vertical, each flexible element having its lower end connected to one of said anchoring elements below the surface of the earth.

3.5. A dock construction comprising a plurality of floats cooperating to form a dock of predetermined shape, a plurality of anchoring elements completely embedded in the earth beneath the

water, and at least two normally slack flexible elements connected to each float at oppositely facing portions thereof and diverging downwardly at substantially uniform angles to the vertical, each of said flexible elements being in the form of a relatively heavy chain having its lower end connected to one of said anchor elements at a point spaced below the surface of the earth.

3.6. A dock construction comprising a plurality of floats cooperating to form a dock of predetermined shape, a plurality of anchoring elements completely embedded in the earth beneath the water, each float being substantially elongated in the direction parallel to the next adjacent float, and a pair of normally slack flexible elements connected to each end portion of each float, the pairs of flexible elements of each float diverging downwardly from each other at substantially uniform angles to the vertical and each being connected at its lower end to one of said anchoring elements below the surface of the earth.

3.7. A dock construction comprising a plurality of floats cooperating to form a dock of predetermined shape, a plurality of anchoring elements in the form of piles driven into the earth beneath the water and having their upper ends terminating beneath the surface of the earth, and a pair of normally slack relatively heavy chains connected to each end portion of each float, the pairs of chains of each float diverging downwardly at substantially uniform angles to the vertical and each having its lower end secured to one of said anchoring elements at a point spaced below the surface of the earth.

HENRY O. FOSS.
